(57) **CLAIM**

The ornamental design for a bioabsorbable structural interbody vertebral implant, as shown and described.

DESCRIPTION

FIG. 1 is a left side perspective view of the implant showing the wedge shape, the container hole, and the tabs on each side of the wedge shaped body.

FIG. 2 is a side view showing rounded corners, the wedge shaped body, and the end of the left tab.

FIG. 3 is a top view showing the growth enhancer retaining hole and the protruding tabs; and,

FIG. 4 is a front view showing the tabs thinner than front edge because of the slope of the top face.
